UNITED STATES PATENT OFFICE

167,615

RADIO RECEIVER CABINET

Robert D. Budlong, Skokie, Ill., assignor to Zenith
Radio Corporation, a corporation of Illinois

Application June 19, 1952, Serial No. 20,279

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Radio Receiver Cabinet, of which the following is a specification, reference being made to the accompanying drawing, forming a part thereof.

The figure is a perspective view of a radio receiver cabinet, showing my new design.

The design of the side of the cabinet not shown is similar to the design of the side shown. The design of the rear portion of the cabinet, not shown, is open.

I claim:

The ornamental design for a radio receiver cabinet, as shown and described.

ROBERT D. BUDLONG.
